(57) **CLAIM**

The ornamental design for a light, as shown and described.

DESCRIPTION

FIG. 1 is a top, end, and side perspective view of a light that has the design.

FIG. 2 is a bottom, end, and side perspective view of the light.

FIG. 3 is a bottom and side perspective view of the light.

FIG. 4 is a top and side perspective view of the light.

FIG. 5 is front and side perspective view of the light; and,

FIG. 6 is a side perspective view of the light. The opposite side perspective is a mirror image of this view.

The broken line showing of structural elements on the top of the light is for the purpose of illustrating portions of the light and forms no part of the claimed design.

The two longitudinal sides of the light are translucent and emit some light to the side. The panels forming the sidewalls have a structure on the inner side that may create different visual appearances from different directions, and results in the two longitudinal sides of the light appearing less bright than the bottom of the light.
